-by- Vernon S. Hodges, Attorney

UNITED STATES PATENT OFFICE.

FRANCIS J. STALLINGS, OF EFFINGHAM, ILLINOIS, ASSIGNOR OF FIVE TWENTY-FOURTHS TO MATT FABER AND FIVE TWENTY-FOURTHS TO GEORGE STEPHAN, BOTH OF EFFINGHAM, ILLINOIS.

PLIERS.

1,250,690.

Specification of Letters Patent. Patented Dec. 18, 1917.

Application filed May 14, 1917. Serial No. 168,413.

To all whom it may concern:

Be it known that I, FRANCIS J. STALLINGS, a citizen of the United States, residing at Effingham, in the county of Effingham and 5 State of Illinois, have invented certain new and useful Improvements in Pliers, of which the following is a specification.

My invention relates to an improvement in pliers, and the object is to provide pliers 10 which will afford a gripping engagement from three different points upon the object gripped.

With this object in view, my present invention consists in a pair of jaws pivoted 15 together, a jaw slidably mounted between the pivot, jaws astride the pivot and having means thereon, operated and controlled, whereby said slidable jaw is operated and controlled by cam action of the jaw levers 20 to positively slide said slidable jaw in opposite directions.

In the accompanying drawings,

Figure 1 is a view in side elevation with the jaws apart;

25 Fig. 2 is a similar view showing the position of the parts when the jaws are together or in the gripping position;

Fig. 3 is an end elevation looking forwardly toward the cams; and

30 Fig. 4 is a sectional view.

A and B are the two main levers pivoted together in the usual manner at the crossing point by means of bolt 1 and terminating at their forward ends in gripping jaws 2 and 3.

35 The numeral 4 indicates an intermediate sliding jaw having a toothed end 5, which coöperates with the pivoted gripping jaws 2 and 3. This sliding jaw 4 has a slot 6 extending longitudinally thereof, through 40 which the bolt 1 passes, extending loosely between the crossing or intersecting point of the two jaws 2 and 3.

The levers A and B are provided with inwardly-extending plates in which are 45 formed the slots 7 and 8, which latter extend diagonally in a general direction from one lever toward the outer end of the other lever when the jaws are open, as shown in Fig. 1, they intersecting each other when the 50 jaws are closed in the form of the letter X, as shown in Fig. 2. The sliding jaw 4 is

provided with oppositely-extending studs 9 and 10, which enter the slots 7 and 8 respectively on either side thereof, as clearly shown in Fig. 3, so that the opening and closing of the jaws has the effect of a cam action through the medium of the slots 7 and 8 and studs 9 and 10, which results in forcing the jaw 4 endwise, or, in other words, out toward the ends of jaws 2 and 3 55 when the levers A and B are brought together (as shown in Fig. 2) and in the opposite direction when they are opened or forced apart (as shown in Fig. 1).

In this way a powerful grip is obtained 60 upon the object from three different points simultaneously, without undue strain upon the operator's hands, and thereby providing a simple, inexpensive and effectual article for the purpose.

I claim:

1. Pliers comprising a pair of levers pivoted together and having gripping jaws at one end, a slidable jaw having outwardly projecting studs, the levers having inwardly extending plates which are provided with diagonally disposed slots extending from a point on one lever in the general direction of the pivot and toward the outer end of the opposite lever, said slots receiving 75 the studs on the slidable jaw whereby to impart a positive in and out sliding action to the slidable jaw as the handles are operated.

2. Pliers comprising a pair of levers pivoted together and having gripping jaws at 80 one end, said levers having portions provided with diagonally disposed slots extending at an angle to the general direction of the levers, said portions being spaced apart, and a slidable jaw coöperating with 85 the gripping jaws and extending between said slotted portions, and having studs which enter and are adapted to slide in the slots as a means whereby the sliding jaw is moved back and forth with the movement of 90 the levers.

3. Pliers comprising a pair of levers pivoted together, and having gripping jaws at one end, a jaw slidably mounted between the levers and astride the pivot which holds 100 them together, and provided at the rear or inner end with outwardly-projecting studs,

the levers having diagonally-disposed cam means which receive said stud, said cam means extending from a point on one lever in the general locality of the pivot toward the outer end of the opposite lever, whereby when the levers are forced together the sliding jaw is moved toward the pivoted jaws,

and when said levers are forced apart, in the opposite direction.

In testimony whereof I affix my signature. 10
FRANCIS J. STALLINGS.

Witnesses:

WALTER E. RINEHART,
JOHN F. DIRKS.
